UNITED STATES PATENT OFFICE.

EINAR L. M. SIVARD, OF NEW YORK, N. Y.

DAVIT OR HOISTING AND LOWERING APPARATUS FOR SHIPS' BOATS.

1,258,485.

Specification of Letters Patent.

Patented Mar. 5, 1918.

Application filed June 14, 1915. Serial No. 33,915.

To all whom it may concern:

Be it known that I, EINAR L. M. SIVARD, a citizen of the United States, and a resident of the borough of Bronx, in the county 5 of Bronx and State of New York, have invented certain new and useful Improvements in Davits or Hoisting and Lowering Apparatus for Ships' Boats, of which the following is a specification.

10 This invention relates to improvements in davits or hoisting and lowering apparatus for ships' boats.

By the use of my invention I am enabled to produce a device of the track extension 15 type, as distinguished from the vertical swinging or pivotal types, which will be positively safe and operable under all conditions of employment as, for example, during the rolling of the ship and may be actuated to drive and carry the lifeboat with sufficient speed during a severe list of the vessel; the boat-shifting or boat-carrying means will always be normally and positively locked against accidental movement 20 in any direction and will be controllable and movable solely by a positive actuation of the driving means, the positive act of driving being adapted automatically to unlock and permit movement of the boat-carrying 25 means, and the release by the operator's hand of such positive actuating means causing the carriage again to become locked against movement in either direction and enabling the boat to be lowered or raised 30 from any suitable position without any further separate securing or locking of the carriage.

Furthermore my improved apparatus provides means whereby the hoisting and 35 lowering falls will, during the traversing of the boat from inboard to outboard positions, or vice versa, and the consequent movement of the carriage or slide from which the boat is suspended along the tracks, 40 be caused to render over the block or tackle without a change in the length thereof so as to cause the boat to travel in a path parallel to the track.

Another feature of my invention is the

arrangement of the hoisting and lowering 50 falls or other boat suspending means in such relationship to the movable track-extension, that such falls will during the swinging out of the track-extension not only prevent excessive slack which would have 55 to be taken up before the boat could be lowered but by suitable adjustment of the point of attachment of the standing part of such falls will cause the boat to be slightly elevated so as to lift the same out of the chocks 60 during a downward movement of such extension and all the parts will be in position to be operated the moment the extension reaches the level of the main track section.

Furthermore in my preferred arrangement 65 of the falls, the movement of the extension track from one position to another will cause an initial slackening of such falls and then a tightening thereof as it reaches its other extreme position so that excessive 70 slackness of the ropes may be prevented at all times without interfering with the free movement of said track extension and a cushioning effect of the movement of the extension track will be produced together 75 with a raising or elevating of the boat as above described.

In the accompanying drawings in which similar reference characters designate corresponding parts throughout the several 80 views,

Figure 1 is an end elevation of a lifeboat and hoisting and lowering apparatus therefor embodying my invention;

Fig. 1^A is an end view, looking inboard, 85 of a single track illustrating the arrangement of pulleys at the outer end thereof;

Fig. 2 is a section on the line A—A of Fig. 1;

Fig. 3 is a section on the line B—B of 90 Fig. 1 looking in the direction of the arrow;

Fig. 4 is a section on the line C—C of Fig. 1;

Fig. 5 is a longitudinal section on the line D—D of Fig. 3 partly in elevation of a 95 slightly modified arrangement of the driving and lowering means;

Fig. 6 is an end elevation of another

modified form of hoisting, lowering and traversing devices embodying my invention;

Fig. 7 is a section on the line E—E of Fig. 6;

Fig. 8 is an enlarged detail view of the carriage and contiguous parts shown in Fig. 6;

Fig. 9 is a still further enlargement of a loose tooth construction illustrated in Fig. 8.

Referring now to these drawings 1 indicates the boat deck of a steamer 2.

In the embodiment of my invention shown in Figs. 1 to 5 inclusive I have illustrated my invention as applied to what I shall term an upperdeck davit, though it will be obvious that my invention is equally applicable to an interdeck davit.

In my said preferred construction, two frames, each comprising upright bars or columns, three of which are indicated by the numerals 3, 4 and 5 respectively, are suitably secured to the deck and braced in any suitable well known manner. These uprights or columns of each frame are connected together by yokes 6 and 7 respectively from which yokes are suspended a stationary track 8 in a horizontal position above each end of a lifeboat 9, each track extending transversely to the axis of the lifeboat and of the ship and the tracks of the two frames being parallel and extending inboard any suitable distance so as to enable the movement or traversing thereon of one or a plurality of boats.

Each of such tracks 8 has a hinged extension 8^a pivoted at 11 to the yoke 6 and to the track 8 so that it may either register with and form a continuation of the tracks 8 as illustrated in full lines in Fig. 1, or may be swung upwardly substantially parallel to the ship's side as indicated in dotted lines in said figure.

In the preferred construction illustrated in Fig. 1, the said extension is arranged to swing vertically, though such extension may be arranged to swing horizontally if so desired. The extension track 8^a is preferably supported by a toggle brace 12, which is pivoted at one end to said extension track at 13, and having its other end pivoted at 14 to an extension 15 of the supporting frame. The two parts of said toggle brace are, as shown, pivoted together at 16, and I preferably provide means secured to the pivotal point 16 for raising and lowering the extension 8^a in relation to the stationary track 8. As shown, I attach to the pivot 16 an ordinary block 17 and at a suitable point on the frame fasten a similar block 18. A rope 19 which is connected to the block 16 and passes over the block 17 and thence backwardly over the block 18 to a suitable belaying cleat 20 provides means for hoisting the extension track 8^a to the position indicated

in dotted lines in Fig. 1 and said extension track may of course be held in such elevated position by securing the rope 19 to the cleat 20. When the said track is lowered the toggle brace 12 will brace and retain said extension track in its extended position.

Mounted on the track 8 and movable along said track and also along the extension 8^a when the latter is in its horizontal or registering position is a carriage or trolley 21 rolling on wheels 22.

The carriages 21 on opposite tracks will of course be moved along the same for the purpose of traversing the boat from its inboard to its outboard positions and vice versa, and for this purpose I preferably provide a flexible connection with said trolley which may comprise a chain 24 extending from one end of said trolley 23 outwardly over a suitable rope-leading device preferably of the rotating or oscillating type, such as a pulley 25 pivoted at the outboard end of the extension track 8^a, thence inwardly through a fairlead or aperture 26 in the yoke 6 and over a pulley 27 mounted contiguous to said fairlead, and thence farther in a rearwardly direction around a chain wheel 28 at the inboard end of the track 8, which with its associated elements normally locks said chain against movement in opposite directions as hereinafter described and said chain is thence led forwardly and secured to the opposite end 23^a of the trolley 21, or the said chain may, as is preferred by me, be a continuous or endless chain, as illustrated in Fig. 5, which extends through an opening in the carriage and is releasably connected thereto so as to permit a relative movement between the carriage and the traversing means when it is desired to move the carriage more quickly than it is possible to move the traversing connection.

Such a releasable connection is illustrated in said Fig. 5 in which a chain 24 extends across and through the trolley and is normally connected thereto by means of two oppositely disposed pawls 48 and 48^a respectively, which pawls are integral with levers 49—49^a respectively and are pivoted on shafts 50—50^a fixed in the trolley. These pawls are normally retained in contact with the chain by helical springs 51—51^a and the action of each of such springs is to force the pawl upwardly so as to jam the chain against pointed projecting ridges 54 on cross pieces 53 of the trolley so that the carriage will at all times be locked against movement relative to said chain in opposite directions, and the inclination of the pawls is such that a pull on the chain in one direction will cause a tightening or further jamming of the chain between one of the pawls and its coöoperating ridge and a pull in the opposite direction on the chain will cause

a similar tightening of the connection or jamming of the chain between the opposite pawl and its coöperating ridge.

In order to release the pawls and move the carriage or trolley relatively to said traversing connection or chain I provide handles 55—55^a. Obviously a pull on the handle 55 will cause the pawl 48 to release the chain and when the pawl is so released may 10 be pulled by said handle in one direction, and the opposite pawl will simply slip over the links of the chain. Similarly a pull on the handle 55^a will cause the releasing of the pawl 48^a whereupon the trolley may be 15 moved in relation to the chain in the opposite direction. In this manner it is possible to move the carriage inboard very quickly for the purpose of picking up another boat after launching one boat and under certain 20 conditions, as for example when the ship is on an even keel, this device may be employed to permit the movement of a lifeboat from outboard to inboard position or vice versa.

My preferred means for normally locking the traversing chain against movement in opposite directions comprises, as shown in cross section in Fig. 4, a device which is known as a "double-lift safety hoist". In this device the chain wheel 28, which is provided with a threaded bore, is threaded on a threaded part 29^a of a shaft 29. The shaft 29 is journaled in bearings 36—36^a in a housing 33 on opposite sides of the chain wheel. Loose on the shaft 29 are ratchet 35 wheels 30—30^a respectively, the teeth of which face in opposite directions and are permanently engaged by pawls 31—31^a respectively which are pivoted on shafts 32—32^a in projections of the housing 33. 40 Collars 34—34^a and a hand-wheel 35 are pinned or keyed to the shaft 29 which, as aforesaid, is journaled and free to rotate in said bearings 36—36^a. The hand-wheel is rotated by a hand-rope 37.

45 A pull on the chain 24 in one direction will cause the chain-wheel 28 to be screwed up against a ratchet wheel on one side thereof so as to cause the jamming of the chain-wheel against the ratchet wheel and a consequent locking through the coöperation of the pawl against movement in that direction. An attempt to pull the chain 24 in the opposite direction will cause a similar jamming against the opposite ratchet wheel 55 and a consequent locking against movement in that direction. By pulling the hand-rope to rotate the hand-wheel 35, however, the chain-wheel 28 may be rotated and the chain moved in either direction either with or 60 against any pull on the chain 24. When the chain is thus moved the trolley 21 with which it is connected will of course be moved along the track 8 and 8^a and will be always under positive control and will be unaffected

ed by the movements of the ship, and may 65 be stopped with perfect security at any point along the track for the purpose of lowering a lifeboat therefrom without further securing the carriage or trolley in any manner. 70

Suitable means is provided for suspending a life-boat from said carriage and for lowering the same therefrom, and for this purpose I preferably provide a flexible connection which will have contact points at 75 opposite sides of the pivot 11 of the extension track 8^a so that all excessive slack in the flexible connection will be taken up during the movement of the extension track to its extreme positions and furthermore by 80 such an arrangement I am enabled by a suitable adjustment of the rope and the retaining contact above the pivot to cause a lifting or elevating of the boat from its chocks upon the movement of the extension track 85 to its extended or registering position.

As shown I provide, for the purpose above set forth, a rope or fall 38 which may be fastened in any suitable manner at the inboard end or, as illustrated in Fig. 1, may 80 be wound up and held on a lowering drum 39. The fall 38 passes from the drum 39 upwardly over a pulley 40 on the davit frame to a pulley 41 at the inboard end of track 8 and thence outwardly beneath the pivot 11 of the extension track at which point it is adapted to contact with the track when the said extension is moved to its folded position, thence over pulley 42 which is loose on shaft 43 on the trolley 21, thence 90 down around a pulley 44 in block 44^a which is secured to one end of the life-boat and is then led up over pulley 45 which like pulley 42 is loose on the shaft 43 on the trolley 21. From this point said rope passes outwardly 100 around pulley 46 at the outboard end of the extension track 8^a which is pivoted on the same shaft as the chain pulley 25 but is rotated independently thereof, and thence 105 back, above and contiguous to the pivot 11, to an eye 47 in the yoke 6, to which the end of the fall 38 is permanently secured. The said rope may, instead of being so permanently secured, simply have a retaining contact at or about the position of said eye. 110

When the trolley 21 is moved along track 8—8^a the fall 38 renders over these pulleys 42, 44 and 45 and the lifeboat is thus carried out or in, on a line absolutely parallel to track 8—8^a. 120

When the boat is in the desired position for lowering, the inboard end of fall 38 is paid out, rendering over pulleys 40, 41, 42 and 44 and the boat is lowered.

By locating the eye 47 at a proper height 125 above the pivot 11, approximately at the same distance above as the rope 38 is below, it is possible to move extension track

8^a to registry with the stationary track 8 or vice versa without appreciably changing the tension in rope 38, which during this operation renders around pulley 46. For the same reason chain 24 passes through fairlead 26.

By this arrangement the track extension 8^a can be lowered from its upright position to horizontal position without causing excessive slack in the boat-fall 38 or driving chain 24 which would have to be taken up before the davit could be used and everything is ready for launching the boat the moment the extension 8^a is in place.

Furthermore by simply screwing the eye-bolt 47 in or out or moving the same vertically in a slot a couple of inches, the flexible connection can be adjusted to be either under the same tension when the extension 20 is in extreme positions or tighter when the arm is down than when up. In either case the flexible connections will be slack during most of the movement. The boat may, therefore, be lifted an inch or so out of the 25 chocks in dropping the arm, and the weight of the track will be sufficient to lift even a loaded boat on account of the enormous leverage.

The operation of the apparatus in launching the boat is as follows:

The rope 19 is cast off cleat 20 and the track extension by its own weight let down from position until it forms a straight continuation of the track as 8^a. The weight 35 thereof is then supported by brace 12.

After clearing away boat gripes and chocks in the usual manner and elevating the boat from the keel-rest by the movement aforesaid, the carriages or trolleys 21 on 40 each of the two davits are moved out on their respective tracks 8—8^a by two men each pulling the hand-ropes 37 of their respective davits and the boat suspended from the trolleys is brought out clear of the ship's 45 side to the desired position for lowering which is effected by the paying out of the inboard part of boat falls 38.

It is not necessary that both ends of the lifeboat are brought out simultaneously because the flexibility of the arrangement is 50 such as to allow considerable variations in this respect.

It will be seen that the boat is always under absolute control as the arrangement for 55 moving the same is self-locking and if it is not desirable to bring the boat all the way out before lowering, it may be stopped at any suitable point on the way and lowered from there just as readily and safely.

60 The boat moves out or inboard on a course parallel with the track, so that normally, when the ship is on an even keel, there is only the friction of the moving parts to overcome and as there are no eccentric

wrenching or twisting stresses on the moving parts common to most other types of davits this friction is reduced to a minimum.

The operating mechanism can, therefore, without undue sacrifice of handling speed, more easily than in at present existing types 70 of davits, be made powerful enough to handle the boat under adverse conditions, such as against a considerable list of the ship or when the ship is rolling heavily.

An additional advantage when the ship 75 is rolling is that the boat is suspended very close under the davit, as any desired out-reach can be obtained without increasing the distance between upper and lower blocks 80 of the supporting tackle, as in other davits. In this way the boat is under better control while being brought out.

Under certain circumstances, especially in handling smaller lifeboats, it may be advantageous to use the driving mechanism 85 also as hoisting gear. Fig. 6 illustrates one such arrangement.

In this construction the track 60 may be any suitable section, I-beam, as here shown, preferred. On the trolley 61 the driving 90 mechanism is located; the hand-wheel 62 is actuated by hand-rope 63 which goes around the hand-wheel 62, over pulley 64 at outboard end of the track, from there over pulley 65 at inboard end of same, down in a bight so that it may be operated from the deck and up over pulley 66 at inboard end of the track back to hand-wheel 62. The hand-wheel 62 is keyed to a shaft 67, 95 which is free to rotate in bearings in trolley 61. On shaft 67 is a spur-pinion 68 mounted precisely similar to chain-wheel 28 above described, so that it is self-locking when directly actuated upon by any force at its circumference, striving to turn it, but 100 may be turned in either direction by actuating the hand-wheel 62.

Pinion 68 meshes with spur-gear 69, loose on shaft 70 which is mounted in the trolley 110 61. On the same shaft is a small rope-drum 71 fixed to or cast integral with gear 69, and also rope pulley 72, both loose on the shaft. What corresponds to the inboard part of the hoisting rope or boat fall 73 is belayed on cleat 74 on the framework, passes over pulley 75 and around pulley 76 at inboard end of track to trolley 61, where it is wound several turns around drum 71, and from there down around pulley 77 in lower block up over pulley 72 in the trolley again. 115 From the trolley it passes around pulley 78 at outboard end of the track back over pulley 79 down to cleat 80 on the framework. This part of the rope is joined to the part belayed on cleat 74 forming an endless rope 120 of sufficient length to lower the boat into the water.

On the trolley 61 is pin 81. When the

trolley is in its inboard position against the stop 82, the pin 81 is engaged by the hook 83 on lever 84 pivoted to track 60 at 85. By pulling down the handle 86 the hook 83 is 5 lifted to release pin 81.

The operation is as follows:

When trolley 61 is at the inboard position, held by hook 83, the lifeboat may be hoisted to desired height by pulling hand-rope 63 in 10 the proper direction, the slack in the inboard part of the boat-fall 73 meanwhile being taken up as it comes off drum 71 and belayed on cleat 74. The trolley is then released by pulling handle 86 and a continued pull on 15 hand-rope 63 in the same direction as before will then cause trolley 61 to move outboard on track 60 carrying the lifeboat along on a course parallel to the track as above described. When in desired position, the boat 20 is lowered by paying out the boat-fall from cleat 80.

When the trolley 61 is at the outboard end of track 60, the boat may be hoisted in the same manner as above described when at the 25 inboard position. No hook to hold the trolley is needed at the outboard end while hoisting as the pull in the hoisting rope tends to hold the trolley against the outboard end of the track.

30 When the boat is hoisted high enough, the fall 73 is again belayed on cleat 74 and the trolley is moved inboard by reversing the pull in hand-rope 63.

One advantage of using an endless boat-fall, rove in the manner here described, is that the rope is worn evenly for its whole length and not for only a small part thereof, as usually is the case.

If the boat, while being brought in or out, 40 could always be hoisted close up under the trolley 61 so that the upper and lower blocks of the tackle are close together, this arrangement would give as positive a control during the operation as the arrangement illustrated in Fig. 1.

It may not always be possible to do so, and in that case this arrangement will under all circumstances prevent the trolley from moving outboard except under full control in 50 that direction, but will not prevent the trolley from coming back inboard when the ship is rolling, and therefore, a device must be added to overcome this defect, and insure complete and self-acting control under all 55 circumstances.

A rack 87 is fixed along the track 60 and its outboard extension, so as to mesh with gear 69. Rack 87 does not, however, extend all the way to the ends of track 60. When 60 the trolley 61 is at the extreme inboard or outboard position, gear 69 is out of mesh with rack 87, and the boat may be hoisted, but as soon as the trolley is moved away from either end, gear 69 engages the rack.

As gear 69 also engages the self-locking 65 driving mechanism it is evident that trolley 61 can not move on track 60 except as impelled by the pull in the hand-rope 63.

In order that gear 69 may always mesh properly with rack 87 when engaging same 70 from either end, the first tooth 88 at either end of rack 87 is not fixed, but pivoted on pin 89 in slot 90 in the rack so as to allow a slight movement to either side from its normal position, which it retains by its own 75 gravity.

A tooth of gear 69, striking the tooth 88, will deflect the same to one side or the other sufficiently to slide into its proper space in the rack or nearly so, so that if the second 80 tooth 91 of the rack is slightly rounded, gear and rack will be brought into proper mesh.

As the pitch diameter of gear 69 is equal to the diameter of rope drum 71, gear 69 will move along rack 87 at a speed equal to the 85 speed with which the trolley moves along the track 60 under the pull on rope 73.

Having described my invention, I claim:

1. Hoisting and lowering apparatus for ships' boats embodying therein a pair of 90 parallel tracks suitably secured on the ship and arranged to project beyond the ship's side, a carriage mounted on each of said tracks, means for suspending a lifeboat from said carriages and for hoisting and lowering the same, means for propelling said carriages along the tracks in opposite directions to traverse the lifeboat and means associated with such propelling means for preventing movement in either direction of the 95 carriages except by positive actuation of the propelling means.

2. Hoisting and lowering apparatus for ships' boats embodying therein a pair of 100 parallel tracks suitably secured on the ship and arranged to project beyond the ship's side, a carriage mounted on each of said tracks, means for suspending a lifeboat from said carriages and for hoisting and lowering the same, means, independent of the suspension means, for propelling said carriages along the tracks in opposite directions to traverse the lifeboat and means associated with such propelling means for preventing movement in either direction of the 105 carriages except by positive actuation of the propelling means.

3. Hoisting and lowering apparatus for ships' boats embodying therein a pair of 110 parallel tracks suitably secured on the ship and arranged to project beyond the ship's side, a carriage mounted on each of said tracks, means for suspending a lifeboat from said carriages and for hoisting and lowering the same, means independent of the suspension means for propelling said carriages along the tracks in opposite directions to traverse the lifeboat and means associated 115

120 with such propelling means for preventing movement in either direction of the carriages except by positive actuation of the propelling means.

4. Hoisting and lowering apparatus for ships' boats embodying therein a pair of 125 parallel tracks suitably secured on the ship and arranged to project beyond the ship's side, a carriage mounted on each of said tracks, means for suspending a lifeboat from said carriages and for hoisting and lowering the same, means independent of the suspension means for propelling said carriages along the tracks in opposite directions to traverse the lifeboat and means associated

- 6 with and releasable solely by direct actuation of the propelling means for normally locking the carriage against movement along the track in either direction.
- 5 4. Hoisting and lowering apparatus for ships' boats embodying therein a pair of parallel stationary tracks, a pair of extension tracks normally retained in a position substantially parallel with the side of the ship 10 and pivoted to swing into registry with the said stationary tracks, carriages movable along said stationary and extension tracks; flexible connections associated with said carriages and having a boat suspended intermediate the ends thereof, guiding devices for said flexible connections at the outer ends of said extension tracks and means stationary in relation to said stationary tracks for supporting and controlling portions of 15 said flexible connections on opposite sides of said guiding device to cause the suspended boat to be lifted by the outward movement of said extension track.
5. Hoisting and lowering apparatus for 20 ships' boats embodying therein a stationary track, a movable extension track pivoted at one end to said stationary track to swing from a position parallel to the side of the ship into registry with said stationary track, 25 a carriage movable along said track and means for propelling the same, a flexible connection for manipulating the boat extending on opposite sides of the pivot of said extension track, a guiding device for 30 said flexible connection at the outer end of said extension track, means stationary with relation to said stationary tracks for fastening one end of said flexible connection contiguous to the pivot of said track and 35 means for guiding and supporting that portion of the flexible connection on the opposite side of said guiding device to cause the same to be carried with said track extension when the same is moved.
- 45 6. Hoisting and lowering apparatus for ships' boats embodying therein a stationary track, a movable extension track pivoted at one end to said stationary track to swing from a position parallel to the side of the ship into registry with said stationary track, 40 a carriage movable along said track and means for propelling the same, a pulley at the outer end of said extension track, a rope associated with said carriage 45 and suitably fastened at one end at a point stationary with relation to said stationary tracks and contiguous to the pivot thereof, passing over said pulley and having the portion of said rope at the opposite side of said pulley guided and supported to be carried by and moved with said track extension, means also stationary with relation to 50 said extension track for controlling said last mentioned portion of said rope and a

boat suitably suspended on said rope from 65 the said carriage.

7. Davits for ships' boats embodying therein a stationary track, a movable extension track pivoted at one end to said stationary track to swing from a position parallel to the side of the ship into registry with said stationary track, a carriage movable along said tracks and means for propelling the same, a pulley at the outer end of said extension track, an adjustable fastening device located at a point stationary 70 with relation to said stationary tracks and contiguous to the pivot thereof, a rope fastened to said fastening device, then passing over said pulley and having the portion of 75 said rope at the opposite side of said pulley guided and supported to be carried by and moved with said track extension, means also stationary in relation to said stationary tracks for controlling said last mentioned portion of said rope, and a boat suitably suspended on said rope from the said carriage. 80

8. Hoisting and lowering apparatus for ships' boats embodying therein a stationary track, a movable extension track pivoted at one end to said stationary track to swing from a position parallel to the side of the ship into registry with said stationary track, 85 a pulley at the outer end of said extension track, a carriage mounted on said tracks, an endless traversing flexible connection extending on opposite sides of the said tracks, passing around said pulley, means for causing the parts of said flexible connection to 90 be carried by and moved in substantially parallel planes with said extension track, means for releasably connecting the carriage with said traversing connection and means for raising and lowering the boat from said carriage. 95

9. Hoisting and lowering apparatus for ships' boats embodying therein a stationary track, a movable extension track pivoted at one end to said stationary track to swing from a position parallel to the side of the ship into registry with said stationary track, 100 a pulley at the outer end of said extension track, a carriage mounted on said tracks, an endless traversing flexible connection extending on opposite sides of the said tracks, passing around said pulley, means for causing the parts of said flexible connection to be carried by and moved in substantially parallel planes with said extension track, 105 automatically actuated oppositely-disposed pawls for connecting the carriage with said traversing connection, said pawls being adapted to automatically lock the carriage against movement relatively to said connection in opposite directions and means for independently releasing one of said pawls to permit relative movement of the 110

carriage in one direction while maintaining locking connection against movement in the opposite direction.

10. Hoisting and lowering apparatus for ships' boats embodying therein a stationary track, a movable extension track pivoted at one end to said stationary track to swing from a position parallel to the side of the ship into registry with said stationary track, 5 a pulley at the outer end of said extension track, a carriage mounted to move along said tracks, a traversing flexible connection connected to said carriage extending on opposite sides of said tracks, passing around 10 said pulley, means for causing the parts of said flexible connection to be carried by and moved in substantially parallel planes with said extension track, an independent flexible connection suitably connected at the inboard 15 end of the stationary track, led outwardly beneath said extension track and around said pulley, means for causing the parts of said independent flexible connection to be carried by and moved in substantially parallel 20 planes with said extension track, a pulley at the outer end of said extension track, a carriage mounted to move along said tracks, a traversing flexible connection connected to said carriage extending on opposite sides of said tracks, passing around said pulley, means for causing the parts of said flexible connection to be carried by and moved in substantially parallel planes with said extension track, means releasable solely by direct actuation for normally locking said traversing connection against movement in either direction and an independent rope suitably connected to the inboard end of the stationary track to permit a lengthening and shortening thereof to raise and lower the boat, said rope running over pulleys on 25 the boat, said rope running over pulleys on 30 said carriage, having a boat suspended therefrom and being led outwardly beneath said extension track, around the pulley at the outer end of the extension arm, and means for causing the parts of said independent rope to be carried by and moved in substantially parallel planes with said extension track.

11. Hoisting and lowering apparatus for ships' boats embodying therein a stationary track, a movable extension track pivoted at one end to said stationary track to swing from a position parallel to the side of the ship into registry with said stationary track, 35 a pulley at the outer end of said extension track, a carriage mounted to move along said tracks, a traversing flexible connection connected to said carriage extending on opposite sides of said tracks, passing around said pulley, means for causing the parts of 40 said flexible connection to be carried by and moved in substantially parallel planes with said extension track, means for propelling said flexible connection, means releasable

solely by direct actuation of said propelling means for normally locking said traversing connection against movement in either direction and means for raising and lowering a boat from said carriage.

12. Hoisting and lowering apparatus for ships' boats embodying therein a stationary track, a movable extension track pivoted at one end to said stationary track to swing from a position parallel to the side of the ship into registry with said stationary track, 5 a pulley at the outer end of said extension track, a carriage mounted to move along said tracks, a traversing flexible connection connected to said carriage extending on opposite sides of said tracks, passing around said pulley, means for causing the parts of said flexible connection to be carried by and moved in substantially parallel planes with said extension track, means releasable solely by direct actuation for normally locking said traversing connection against movement in either direction and an independent rope suitably connected to the inboard end of the stationary track to permit a lengthening and shortening thereof to raise and lower the boat, said rope running over pulleys on 10 said carriage, having a boat suspended therefrom and being led outwardly beneath said extension track, around the pulley at the outer end of the extension arm, and means for causing the parts of said independent rope to be carried by and moved in substantially parallel planes with said extension track.

In witness whereof, I have signed my name to the foregoing specification in the presence of two subscribing witnesses.

EINAR L. M. SIVARD.

Witnesses:

HELEN V. HOLMES,
STALLO VINTON.
